UNITED STATES PATENT OFFICE.

JOHN EDWARD THORNTON, OF ROCHESTER, NEW YORK, ASSIGNOR TO JOHN OWDEN
O'BRIEN, OF MANCHESTER, ENGLAND.

METHOD OF AND APPARATUS FOR PRODUCING PHOTOGRAPHIC PRINTS.

1,173,898.

Specification of Letters Patent. Patented Feb. 29, 1916.

Application filed June 21, 1911. Serial No. 634,573.

To all whom it may concern:

Be it known that I, JOHN EDWARD THORNTON, a subject of the King of Great Britain, and resident of Rochester, in the county of Monroe and State of New York, have invented certain new and useful Improvements in Methods of and Apparatus for Producing Photographic Prints, of which the following is a specification.

10 This invention relates to the manufacture of a photographic strip of film-tape provided with a succession of views or images.

It is particularly applicable to the manufacture of films for use in motion-projection, 15 though it is also applicable wherever a large number of views or images must be printed and developed.

The object of the invention is to provide a method, and apparatus for carrying this 20 method into practice, whereby printed strips of considerable or indefinite length may be produced by a continuous operation, so that the blank material may be introduced continuously at one point in the apparatus and 25 discharged continuously in finished condition at another point.

An important feature of the invention consists in the manner in which the strip is 30 led through the several chambers or receptacles in which it is treated. Instead of leading the strip in a direct course, or in a zigzag or tortuous path as has been previously proposed in connection with more or less analogous operations, I conduct the 35 strip over suitable drums or rollers in such a manner that it follows a path which may be described as substantially helical in form. This is accomplished, in the simplest manner, by coiling the strip repeatedly and helically around two substantially-parallel chamber rollers, and the extent of departure 40 of the path from a true helix depends upon the distance between the rollers. In any case a valuable characteristic of the arrangement resides in the fact that in a comparatively limited space a great length of the 45 strip may be coiled and at the same time fully exposed, while the strip may also pass continuously, at any required speed, through 50 this path when the rollers are caused or permitted to rotate by the application of power.

As compared with a zigzag path the pres-

ent arrangement has several pronounced advantages. In the first place, it causes the portions of the material in successive turns 55 to lie all in the same plane and with the sensitized surfaces facing in the same direction, which is of particular utility in the printing operation, as it permits the use of actinic light falling upon the successive turns 60 from the same direction, thus simplifying the arrangement of the sources of light and economizing in the expenditure of energy. In the second place the novel arrangement permits the use of very simple mechanism 65 for supporting and moving the strip, since two rollers, sufficiently elongated, may be used to support any required length of material. A third advantage of the present arrangement resides in the fact that the material is not bent alternately in opposite 70 directions, as in the case where guides are arranged to form a zig zag path, but is bent always in the same direction in successive turns about the rollers. 75

A further feature of the invention resides in the novel manner in which the printing operation is made continuous. To this end I employ an endless transparent film, which may be either a negative or a positive according as it is desired to produce positive or negative prints, and this film is moved constantly at the same speed as the sensitized strip to be printed, so that the two strips travel in contact through a certain space in 80 which they are exposed to actinic light and the endless negative or positive film is thus used over and over to print successive portions of the sensitized strip. 85

Other objects and features of the invention will be set forth in connection with the following description of the apparatus illustrated in the accompanying drawings. 90

In the drawings, which are diagrammatic in character, Figure 1 is a sectional side elevation of a printing apparatus constructed in accordance with the present invention. Fig. 2 is a section on the line 3—3 in Fig. 1. 95

The invention is applicable to the production of finished photographic material of 100 various kinds in strip form, but as it is particularly applicable to the production of films for use in projecting-lanterns I have illustrated an apparatus designed particu-

- larly for this purpose, and in the following description the material to be acted upon will, for convenience, be designated herein-after as the "film," while the endless film 5 through which the sensitized film is printed will be hereinafter designated as the "negative", although obviously a positive film may be used for this latter purpose where it is desired to produce negative prints.
- 10 The characteristic arrangement of parts by which the film is conducted in a helical path is preferably employed in the illustrated apparatus. The two rollers about which the film passes may be arranged in 15 either vertical or horizontal relation, but they are most conveniently and compactly arranged in vertical relation, one roller 1 being journaled near the ceiling of the room or compartment 2, and the other roller 3 being journaled near the floor.
- 15 The film 4 is shown as comparatively wide for convenience in illustration, but in actual practice the invention is particularly applicable to narrow film-strips, as these 20 form more readily to the helical path around the rollers. The film passes first upward to and over the roller 1, thence descends directly to the roller 3 and under the latter, and is then led up again to the roller 1 and 25 so on continuously. In the drawings most of the turns of film are omitted for simplicity in illustration. The film is caused to travel through the apparatus by rotating the upper roller 1. To this end this roller 30 is mounted upon a power shaft 5 journaled in shaft-hangers 6 depending from the ceiling, and is provided with a pulley 7 or equivalent means whereby the apparatus may be driven from any suitable source of 35 power.
- 40 The film 4 passes downward to a guide-roller 8, and thence horizontally into the printing chamber or compartment of the apparatus. Beneath the guide-roller 8 is a 45 pressing-roller 9. The negative film 10 is in the form of an endless strip, so that it is employed over and over indefinitely in printing successive portions of the film-strip 4. The negative passes under and around 50 the pressing-roller 9 and into engagement with the film-strip 4, and the two strips thereafter travel in contact with each other through the printing chamber or compartment.
- 55 In order that the registration of the two 55 films may not be disturbed while the printing operation is taking place, relative motion of the films must be absolutely prevented. In my co-pending application, Serial No. 616,506, filed March 23, 1911, I have 60 disclosed a method of securing films together during the printing operation, which consists in cementing them with rubber cement, or other suitable adhesive, and in the illustrated apparatus I employ this method. To

this end a roller 11 engages the lower surface of the negative 10 immediately beneath the pressing-roller 9, and the roller 11 dips into a supply of adhesive contained in a receptacle 12, which is thus applied to the 70 negative. As the same cement may be used over and over it is unnecessary to apply fresh cement constantly to the negative, and accordingly the roller 11 is shown as provided with a lever 11^a for throwing it into 75 or out of engagement with the negative. The cemented films enter the printing chamber horizontally, and pass around and upwardly from a guide-roller 13 to the upper drive-roller 1. They then follow a helical 80 course around the roller 1 and the lower roller 3, from one end to the other of the printing chamber. In the construction shown, the rollers are provided with peripheral flanges 1^a and 3^a respectively which 85 guide the film.

The light by which the printing is performed may be produced by any convenient source such, for example, as mercury-vapor lamps 14. These lamps are arranged in a 90 bank within the path of movement of the films, and the films, in passing from the guide-roller 13 to the roller 1, are given a quarter turn by which the negative is brought to the inner position, so that the 95 light from the lamps passes first through the negative and thus to the sensitized surface of the strip 4.

The front of the printing compartment 100 may be provided with a door 15 to afford access to the interior. To shield the film against the heat of the lamps, transparent sheets 16 are interposed between the lamps and the film, and these sheets may be ruled gratings, heat-absorbing cells, or any well-known or suitable devices for absorbing radiant heat. For the same purpose cool air is introduced through an opening 17 in the door, the heated air being withdrawn from the ton of the compartment through a 105 conduit 18.

The printing apparatus just described is particularly adapted for use in connection with the bichromate process as it permits the film to be exposed for a long period to 110 the action of the light. Obviously where more rapid sensitive material is employed such a long exposure is unnecessary. As the length of the negative varies according to the number of views, it is necessary to 115 provide for adjustment of the length of the path through which the negative is extended. For this purpose the guide-roller 13 is mounted on a lug 19 which is adjustably supported by a horizontal beam 20 extending from end to end of the printing compartment. By adjusting this guide-roller along the beam the film may be arranged to make any required number of 120 turns about the rollers 1 and 3 less than the 125 130

full number, and thus the length of negative in contact with the sensitized film is regulated. The exposure is correspondingly regulated by regulating the sources of illumination.

5 After the completion of the printing operation the film 4 is separated from the negative. As shown in Fig. 1, the strip 4 passes to the right around and under a 10 guide-roller 21, while the negative passes to the left under a guide-roller 22 and returns to the pressing-roller 9, the two films being thus drawn apart. Means may be provided for removing from the surfaces of the film- 15 strip any cement which may remain thereon, and to this end I have illustrated a roller or rotary brush 23 which dips into a supply of suitable solvent, such as gasolene, in a reservoir 24. This roller engages the sur- 20 face of the film, and to rotate the roller at a speed different from the surface speed of the film the roller is connected, by a belt 25, with a pulley 26 on the end of the roller 1. After the film leaves the printing chamber 25 it may be treated to the usual developing, fixing, washing and drying operations.

The apparatus just described is adaptable, by modifications which will be obvious to those skilled in the art, to the performance of any of the ordinary printing operations by which a strip of printed photographic film, or other material, may be produced, the helical path followed by the film being of utility in connection with all of 35 such processes. The invention is not, therefore, limited to the details of construction and arrangement of the illustrated apparatus, but may be embodied in various other forms within the nature of the invention as 40 it is defined in the following claims.

The method of developing and the apparatus therefor are not claimed herein but form the subject-matter of a divisional application, Serial No. 766,595, filed May 9, 45 1913.

I claim—

1. The method of producing photographic prints which consists in immovably securing together, relatively to one another 50 a strip of sensitized material and an endless strip of transparent printed film strip, and moving these strips in such condition past an actinic light to print the sensitized strip through the printed film strip, said printed film strip being continuously returned to the starting point for coöperation with 55 fresh portions of the sensitized strip.

2. The method of producing photographic prints which consists in cementing 60 together a strip of sensitized material and an endless transparent printed film strip, moving said strips simultaneously and in printing relation past an actinic light, detaching said strips as they emerge from the 65 influence of the light, and returning said

printed film strip continuously to the starting point for coöperation with fresh portions of the sensitized strip.

3. The method of producing photographic prints which consists in moving a 70 strip of sensitized material and an endless transparent printed film strip simultaneously and continuously while in contact in a substantially helical course past an actinic light with the printed film strip arranged between 75 the light and the sensitized material, and returning the film strip continuously to the starting point for coöperation with fresh portions of the sensitized material.

4. The method of producing photographic prints which consists in cementing 80 together a strip of sensitized material and an endless transparent printed film strip, moving said strips in such condition simultaneously and continuously while in contact 85 past an actinic light in a substantially helical course with the printed film strip arranged between the light and the sensitized material, separating said strips after they are subjected to the light, and returning the 90 film strip continuously to the starting point for coöperation with fresh portions of the sensitized material.

5. Apparatus for producing photographic prints comprising movable guiding means 95 upon which a strip of sensitized material may be wound in a substantially helical path, means being provided for supplying said strip continuously at one end of said path, means being provided for removing 100 said strip continuously from the other end of said path, and means for feeding a printed film strip to travel in printing relation with said sensitized strip.

6. Apparatus for producing photographic prints having, in combination, two elongated guide rollers arranged with axes substantially parallel and separated by a substantial distance whereby a transparent printed film and a strip of sensitized material may be wound helically about said rollers with substantial portions of the lengths of said film and strip stretched in two planes between the rollers, means co-operative with the film to guide the said film and strip to and from said rollers, means being provided for supplying the sensitized strip continuously to and withdrawing it continuously from said rollers to cause said film and strip to travel together in a helical 110 path about the rollers with the printed film 115 in position for printing the sensitized strip, and a source of actinic light for subjecting the sensitized strip to printing action through the printed film while the printed film and sensitized strip are moving in contact with one another.

7. Apparatus for producing photographic prints having, in combination, means for guiding and moving an endless transparent 120

printed film and a strip of sensitized material in a predetermined path, means for guiding a portion of the printed film into contact and printing relation with a portion 5 of the sensitized strip before the latter passes through said path, means for cementing the film to the strip before the film coöperates with said guiding means, means for separating said film and strip after coöperating

with said guiding means, and a source of 10 actinic light to subject the film and the strip to a printing operation while traveling in said path.

JOHN EDWARD THORNTON.
